Des. 74

Ezra Ripley, Troy, N. Y.

Letters Patent (Design No. 74) dated 25 July 1846
and dated May 28th 1846

The Schedule referred to in these Letters Patent
and making part of the same.

To all to whom these presents shall come:

Be it known, that I, Ezra Ripley of Troy, in the County of Rensselaer, and State of New York, have invented or produced a new design for stoves, and that the following is a full, clear and exact description of the same, reference being had to the accompanying drawings, making part of this specification in which fig. 1. is a view of the end plate, and figures 2. of the side plate.

The same letters indicate like parts in all the figures.

This design is intended to be cut in metal in bold relief and is composed of gothic ornaments having a bold foliated cornice (2) below which the side is divided into three compartments (b, c, d) by perpendicular pendants (d) which terminate in points above the bottom and under which there is a projecting plain moulding (e). The centre compartment (c) is deeply recessed and the ground work is diamond or cross barred. The end is similar in its combination of raised and scroll work &c. to the centre compartment as is fully delineated in fig. 1.

I claim as my invention and desire to secure by Letters Patent the above design which is fully set forth in the drawings accompanying this description -

ED
J. R. A. P. Browne
